BOILING AND CONDENSING HEAT TRANSFER APPARATUS

Crosby Field, Brooklyn, N. Y.

Application July 25, 1932, Serial No. 624,541

15 Claims. (Cl. 126—370)

My present invention relates to systems wherein mercury is boiled to produce vapor, the vapor is circulated through a suitable conduit circuit, including one or more roasters, driers or other devices which absorb the heat from the vapor to condense it, and from the latter the liquid mercury flows by gravity to the boiler. In such systems desired temperatures are maintained by suitably regulating the pressures to raise or lower the boiling and condensing points.

According to my present invention, the system may be operated at, above, or below atmospheric pressures; and the system includes devices for controlling the pressures of the vapor in various parts of the system so that the boiler may be operated at a suitable pressure and temperature for boiling, while one or more of the devices to be heated may be operated at any desired lower pressure and temperature; also different devices supplied by the same boiler may be operated at temperatures and pressures differing one from another.

Preferably, the boiler and vapor distributing part of the system has a high vacuum pump adapted for operating to reduce pressure below atmosphere; and rise of pressure is limited by an automatic relief valve whereby when a predetermined maximum internal pressure is exceeded, the vapor is vented to a safety condenser. Preferably, the automatic relief valve is a mercury bubbler wherein a static head of liquid mercury is maintained at a normally constant level and a novel feature of the arrangement includes providing an overflow outlet for liquid mercury at a desired level, in combination with a return conduit from the safety condenser whereby the condensate is first applied to replenish any liquid that may be blown out of the safety bubbler, excess liquid from the overflow being returned to the boiler.

A valve device also depending on differential depth pressures of liquid mercury, is employed for controlling the flow of vapor to the roaster or other device to be heated. In this device, the differential pressure required for depressing the liquid mercury and permitting escape of the vapor to the roaster, is pressure much greater than that of the bubbler relief valve; and the valve construction may be accurately predetermined for a certain pressure differential between the boiler supply and roaster condenser; whereby the vapor will be supplied to the roaster at rates sufficient to maintain only its required lower internal pressure condition. This valve

device has a predetermined overflow level to predetermine a minimum differential pressure of the liquid mercury, which must be exceeded by the boiler pressure, before the valve can open; together with special means whereby condensate is automatically supplied to replenish overflow or evaporated mercury in said valve, and so restore the desired normal depth pressures and liquid levels. This control valve differs from the bubbler in that, during normal operation, the 10 depth pressure of the mercury may be increased or decreased by increase or decrease of gas or air pressure applied to the surface of the mercury in the overflow level part of the valve. Air or gas admitted to control the level of this 15 overflow surface of the mercury is absolutely precluded from entering the vapor system by providing U-trap tubes, one between the overflow and valve, and one in the drain pipe from the overflow, below the point of admission of said 20 air or gas; both of these traps being of sufficient vertical height to more than sustain full atmospheric pressure on their air or gas engaging surfaces, as against a complete vacuum on their other surfaces.

The normal overflow level of the valve may be arranged a predetermined distance above the level of the vapor inlet to the valve, such that the valve cannot open at a pressure low enough to endanger the operation of the boiler. The external means for regulating air or gas pressure on the mercury within the overflow makes it possible to shut off mercury vapor from the body of the roaster at will and to permit entrance of the mercury vapor whenever desired.

As concerns normal operation, the heights of the liquid columns in the valve chamber and in the overflow chamber are such as to afford a normal differential depth pressure whereby the boiler and conduits leading to the roaster may be 40 maintained at a comparatively high mercury vapor pressure, say, 6 lbs. per square inch absolute, while the pressure in the jacket of the roaster may be nearly a perfect vacuum, say 0.004 lb. per square inch. In such case, the difference 45 in heights of the liquid columns in the valve, will be approximately 12 inches, as is necessary to sustain the desired pressure differential of 6 lbs.; and the valve surface of the mercury may then be depressed below or forced above the level of the valve outlet. Whenever the internal pressure in the roaster falls below desired normal, the sealing surface of the mercury in the valve supply outlet is depressed and the valve outlet 50 55

is unsealed, thereby permitting vapor to flow freely into the jacket of the roaster until the internal pressure in the latter is raised to normal. Similarly when the sealing surface of the mercury is forced upward, the valve is closed. Thus in normal operation, a temperature in the roaster corresponding to a low mercury vapor pressure may be obtained by intermittent opening and closing of the valve; or, what may be called a "puff" method of operation. The alternate opening and closing of the valve permits successive injections of small quantities of hot mercury vapor at each operation. This vapor expands suddenly, producing the lower pressure and the desired lower temperature required for the roaster jacket.

An important utility of the above arrangement is that when the roaster is to be initially heated, the control pressure on the mercury surface of the valve overflow may be reduced enough so that the 6 lb. boiler pressure will depress the sealing surface of the mercury in the valve, thereby keeping the valve open, thus freely supplying the roaster with mercury vapor at boiler pressure and correspondingly high temperature, thus shortening time required for the heating of the roaster to normal operating temperature.

From the above, it will be evident that both the bubbler safety valve and the automatic control valve give control of the mercury vapor without presenting any metallic surface, other than liquid mercury, at the valve seat so that there is never any necessity for replacing valves or valve seats, and in case of accident whereby the liquid mercury is displaced so as to unseal the valve, it is automatically replaced by condensate which refills it to its normal overflow level. An important practical feature of both valves consists in heavily insulating the conduit through which the hot vapor flows vertically downward to the mercury sealed outlet. Such insulation is of great practical advantage in minimizing or preventing boiling of the liquid seal mercury which comes in contact with said conduit when the valve is sealed.

The above and other features of my invention may be more fully understood from the following description in connection with the accompanying drawings, in which

Fig. 1 is a more or less diagrammatic view of the complete system embodying my invention;

Fig. 2 is a characteristic vertical section showing the safety bubbler on a larger scale;

Figs. 3, 4 and 5 are diagrammatic views of the control valve, on a large scale, showing characteristic stages, warming up, open valve relations and closing valve relations, respectively; and

Fig. 6 is a view of said valve on a much larger scale, showing details of construction more fully, showing the mercury level under extreme valve closed conditions, and graphically indicating characteristic depth differentials of the counter-balancing mercury columns at all of the characteristic stages of operation.

The showing of the system in Fig. 1 is necessarily diagrammatic to a certain extent, but in view of the fact that many of the more important features of operation depend upon absolute and differential depth pressures of the liquid mercury, an attempt has been made to make the vertical distances in correct proportion, so far as concerns the parts of the apparatus where this factor is functionally important.

The main elements of the system are a mercury

boiler A for supplying mercury vapor at desired high temperatures, as determined by the absolute pressure maintained in the boiler; one or more roasters or other jacketed containers or utensils B to be heated by the vapor; a pressure operated mercury vapor valve C for controlling flow of the vapor to the roaster; an after condenser D preferably connected in shunt across the cutlet from the roaster for condensing uncondensed vapor and collecting any non-condensable gases; together with suitable lead and return pipes, traps, sumps, etc. In a shunt circuit across the vapor supply main and the liquid mercury return, is a vapor circuit through a safety bubbler E, controlling excess pressure by permitting escape of mercury vapor to a water-cooled safety condenser F, supply of water to which is through float controlled inlet valve V. From F the condensate flows back to the safety bubbler to maintain the depth pressure of liquid therein; thence through suitable sumps and traps, back to the boiler A.

The above elements and their functioning in the system may be more easily explained in connection with a specific illustrative case, as, for instance, where the pressures are all less than atmosphere, the boiler operating at approximately 6 lbs. per square inch, absolute; safety bubbler at 8½ lbs.; and roaster at 0.004 lb.

In Fig. 1, the boiler A is conventionally indicated as being of the depending-tube type in which liquid mercury flows down through an inner tube and is boiled in the annular space between it and the outer closed bottom tube, the latter being heated by a furnace, not shown. For present purposes, it is sufficient to note that the boiler will be designed, and the heat of the furnace will be adjusted with reference to the normally required output of mercury vapor, at the pressure selected for normal operation of the boiler; and when designed for operation at a given pressure, as, for instance, 6 lbs. absolute, it is undesirable to attempt operation at a much lower pressure, say, 2 lbs., because of the much greater volume of vapor that will be boiled off by the same number of heat units, at the lower pressure. My novel means for preventing too great fall of boiler pressure during otherwise normal operation, will be more fully explained hereinafter.

The vapor from the boiler flows through conduit 1 to down-take pipe 2 leading to control valve C of a roaster B. As indicated, the conduit 1 may be extended to down-take pipes supplying other control valves and roasters which may be supplied in parallel with the one shown in Fig. 1, and which may have their control valves designed or adjusted for any other desired roaster pressures and temperatures, within the limits permitted by the design or adjustment of the vapor supply circuit.

From conduit 1 there is a shunt circuit through pipe 1a, to the safety bubbler E, controlling vent of vapor to safety condenser F, from which latter, the condensate flows to the bubbler, and excess passes back to the boiler.

It will be understood that all pipes and as far as possible all valve parts are preferably of heavy seamless tubing, all joints being carefully electrically welded so as to seal the entire system against inleak of air or outleak of mercury vapor. The boiler part of the system is preferably supplied with a pressure indicating gauge 3, the normal working pressure of the boiler being illustratively indicated on Fig. 1 as 6 lbs. to the square inch absolute, which corresponds to a boiling temperature of 591° F.

A pump (not shown) capable of highly evacuating the system is connected with various parts of the system through independently operable valves, the vacuum line connection for the bubbler 5 E and condenser F being controlled by valve 3; that for the main distributing conduit 1, by valve 4; that for the after condenser and roaster jacket circuit, by valve 5; and that for the pressure control portion of valve C, by valve 6.

As shown in Fig. 1, and on a larger scale in Fig. 2, the safety bubbler E comprises a vapor inlet pipe which may be an extension of 1a, and in a particular case may be a 4 inch tube. This tube extends down into liquid mercury in a valve casing 10 which may be 7 inches in diameter closed at the end by a welded quarter inch plate 11, and at the top by washer 12. In normal operation, the inner surface of the down-take pipe 1a is heated by mercury vapor at the working temperature (say, 591° F. at 6 lb. pressure), while its outer surface is in contact with a portion of the sealing liquid mercury which has a much lower boiling point because the pressure on it is 6 lbs. less. So an important feature is providing said down-take pipe 1a with very substantial heat insulation to retard boiling off of the sealing liquid. This insulation may conveniently take the form of a jacket tube 13 secured around tube 1a by welded washers as indicated. Preferably, the space between 1a and 13 is filled with a highly heat resistant insulating material such as magnesia or fire clay.

Casing 10 has an overflow outlet 14, the overflow level of which is above the level of the open end of pipe 1a by a distance corresponding to the desired relief pressure at which the bubbler is intended to operate. In the illustrative case where the normal operating pressure of the system is supposed to be 6 lbs., this vertical distance may be 19 inches, affording a differential depth pressure. Theoretically, this would vent when the boiler pressure on the inner surface of the sealing liquid reaches 9½ lbs., as against the nearly zero pressure which is maintained on the surface of the outer counterbalancing column. However, the high temperature of the liquid mercury in the valve increases its fluidity and decreases its specific gravity to such an extent that in practice, the measured differential of 19 inches, will permit relief at approximately the 8½ lbs., above assumed as the desirable relief pressure.

Mercury escaping through overflow 14, passes into separator chamber 15, wherein any vapor entrained in the liquid is separated therefrom and escapes upward through pipe 16 leading to safety condenser F, while the liquid part flows downward through pipe 17, sump 18, trap 19 and return 20 to sump 21, whence the liquid flows to the boiler through trap 22.

Vapor evaporated in the bubbler or blown through the same during relief operations, passing through pipe 16 is liquefied in condenser F and flows downward, primarily through pipe 23, sealing trap 24 and re-enters the valve at 25. It will be noted that the point of re-entry at 25 is substantially below the overflow level 14, and by this arrangement the sealing mercury in the bubbler is always kept up to the overflow level. As it is not desirable to have large quantities of liquid mercury passing through the bubbler, there is a by-pass 26, through which excess mercury may pass directly downward to sump 18 as, for instance, when greatly excessive

pressure in the boiler causes large quantities of vapor to flow through the bubbler.

The structural parts of control valve C are similar to those of the safety bubbler, as concerns the use of seamless tubing, electrically welded closures, insulating jacket for the vapor inlet pipe 2 but, as will be evident from the detail view Fig. 6, various features such as the functionally important vertical dimensions, manual and automatic pressure controls, etc., are specifically different, as is necessary to take care of the various special conditions and functionings of said valve.

Referring to Fig. 6, vapor downflow conduit 2 is shown as surrounded by insulating jacket 33 and the external valve casing 30 is closed at the bottom 31 and top 32, but the outlet 34 to the condensing roaster jacket, is much higher above the valving level c, than in the bubbler; and the top 32 is preferably inclined at an angle of 45°, so as to deflect away from outlet 34, any liquid mercury that may be projected upward by the incoming vapor, at times of opening and closing of the valve seal. The overflow outlet 35, which determines a normal datum level for the liquid mercury in the valve leads from a chamber 36, instead of directly from the valve casing, and it discharges into a separating chamber 31, whence liquid mercury flows downward in pipe 38 to the liquid return conduit and the boiler sump, through a trap 41a. Preferably, this trap affords a differential depth pressure of mercury sufficient to withstand greater-than-atmosphere pressure differentials both from and toward the overflow. The chamber 36 is connected with the bottom 31 of the valve chamber 30 through a U-tube affording counterbalancing liquid mercury columns in the legs 39, 40. Preferably, each of these columns 39, 40 is of a height substantially greater than the 30 or 32 inches which would be necessary to sustain 40 a full atmosphere-vacuum differential of 15 pounds.

Having the overflow thus arranged in a separate chamber cut off from the valve by the U-tube 39 and from the liquid return system by trap 41a, each capable of sealing against atmospheric-vacuum differentials, in both directions, makes it safe, as well as possible, to apply control pressures to the upper overflow surfaces of the liquid, independently of the boiler-valve-roaster circuit, and as before stated, this control is operated by opening valve 6 to the vacuumizing pump when the pressure is relieved or to a pressure source which may be either by air leak through valve 6, which is ordinarily used for vacuumizing; or it may be by inlet through valve 7, of air or gas, preferably nitrogen or carbon dioxide.

Provision is made for supplying condensed mercury to the overflow chamber and to the valve by means of an uninsulated condenser branch pipe 41 leading from the low pressure conduit 34 which supplies the roaster. This condenser supplies the replenishing condensate to the valve system through pipe 42, which is preferably of smaller diameter and delivers the condensate at the bottom of the U-tube, 39, 40.

In Fig. 6, the liquid is shown at the highest levels attained in the valve and overflow after the valve has been fully closed by application of a full atmospheric 15-lb. control pressure through valve 7; and after the condenser 41 has had time to fully restore the liquid level in overflow chamber 36, which will have been depressed by said control pressure.

The legends on this Fig. 6 indicate said maxi-

mum control pressure of 15 lbs. applied to the overflow surface, and that it is applied as against 6 lbs. supply pressure, and 0.004 roaster pressure. The legends also indicate in inches, the theoretical vertical distances between characteristic levels corresponding to all characteristic stages of operation of the valve, said theoretical distances being subject to slight correction for the working temperature of the liquid mercury in any given case. These vertical distances may be more fully explained, in logical sequence.

The system is evacuated by operating the pump with valve 7 closed and valves 3, 4, 5, 6 and 8 open.

When it shall have been determined that the system is tight and down to approximately 0.004 lb. per square inch absolute pressure (approximately 0.2 mm.) then valves 3, 4, 5 and 8 are closed, thus separating the system from the vacuum pump which still continues to operate, however, on valve 6.

The boiler is then fired and slowly brought up to temperature. At the very low absolute pressure of about 0.004 lb. per square inch (0.2 mm.), the vapor begins to travel through the system. Vapor flows through empty safety bubbler and condenses in the tube 18 and condenser F. Condensate from the latter flows through pipe 22, 24, 25 until it has reached a level that balances the pressure of the vapor in pipe 1a. At this point the bubbler seals and further vapor flow is prevented. As the pressure in the main line increases, it will blow vapor through the liquid, into the condenser, and the condensate will return through 23, until the overflow level 14 is reached. Should the amount of mercury vapor be too great, as in case of very high pressure, then the mercury will rise to a point where any additional liquid mercury will flow over into separating chamber 15, through pipe 17, sump 18, and trap 16, sump 21, and thence to the boiler. When the pressure in 1a becomes less than that due to the differential liquid pressure of the cylindrical column in 1a and the annular column in 18, then the bubbler will reseal. As the pressure reduces to normal and further condensate flows down through 23, 16 or 1a, into casing 10, the height of mercury in the latter will increase until it overflows at 14, and returns through pipes 15, 17, sump 18, etc., to the boiler.

In the meantime, vapor has been flowing through 1 into control valve C, where some of it condenses; also through roaster jacket circuit where more of its condenses, thus accumulating some mercury in the valve and in the low level sumps and traps leading to the mercury boiler; but the safety bubbler being sealed for the then pressures, attention may be directed to the control valve.

Fig. 3 indicates a stage where the increasing amount of liquid in the bubbler is causing the pressure to increase from minimum which may be 2 lbs. to normal which may be 6 lbs. absolute. During this period, the valve is of course wide open and the vapor is passing freely to the roaster at a pressure correspondingly increasing from 2 lbs. to 6 lbs.

The operation of condensing vapor in 41 to seal the valve may be greatly accelerated by opening valve 51 to spray water on said condenser. Condensed mercury falls through the pipe 42 to the bottom of the U-tube and the level of the liquid gradually rises until at some pressure, say about 3 lbs., the levels in 48 and 42 which are under boiler pressure, will be as shown in Fig. 3, while the level in control chamber 36

will be substantially higher because its surface is still exposed to the original approximate vacuum of 0.004 lb. The levels continue to rise in this way until the liquid in 39, 36, reaches the overflow 35 and, as shown in Fig. 4, at this time the boiler pressure and drier pressure will have risen to 6 lbs. while the control pressure remains a substantial vacuum as before. At this time, the sprayer 51 will be turned off and will not be used until it is necessary to again fill the valve. During normal operation, replenishment of liquid will be provided by ordinary condensation in pipes 41, 42, and by entrained liquid, if any, from pipes 1 and 2. At this time, the differences of level will be approximately 12 inches as indicated in Fig. 4, this corresponding to 6 lbs. pressure differential. This is the condition of normal operation during open-valve periods.

The vacuumizing of the overflow through valve 6 may be discontinued and inleak of air or nitrogen through 6 or 7 may be permitted to raise the pressure on the overflow surface to full atmospheric of 15 lbs. as indicated in Fig. 5. Thereupon the mercury level will be depressed in the control chamber forcing upward the liquid in the valve chamber until a 9 lb. differential (15 lb. minus 6 lb.) is established by 18 inches of differential head. The valve 5, connecting the roaster jacket and condenser with the vacuum pump, will then be opened enough to reduce the working pressure in the roaster jacket to the normal working pressure, which in this case is supposed to be 0.004.

While this reduction in roaster jacket pressure is being effected, condensation in the down pipe 2 and in condenser 41 will operate as shown in Fig. 6, to replenish liquid in the control chamber and in the valve until, as shown in Fig. 6, the level in the control chamber will reach the level d which is that of the overflow 35; then the level in 2 which is at 6 lbs. pressure will reach the level e, which affords an 18 inch differential which equals 9 lbs. of pressure, and the surface of the mercury in 39 will reach the level f which is 12 inches higher than e, representing the 6 lb. boiler pressure balanced against the practical vacuum in the roaster. The total differential d-f remains 30 inches, representing the full differential between control surface 35, which is at the 15 lb. pressure, and the annular surface in 39, which is practically complete vacuum.

Preferably, the vacuumizing valve 5 controlling roaster pressure is run slightly open at all times when non-condensable gases are present, so that the absolute value of the vacuum pressure will be practically constant. As we have seen, the safety bubbler prevents the supply pressure in 2 from rising more than about 2½ lbs. above the normal 6 lbs. optimum pressure for the boiler; while lowering of boiler pressures below 2 or 3 pounds is prevented, by reason of the normal predetermined difference of level c-d, between the sealed outlet of pipe 2 and the overflow level of the control surface at 35. In normal operation, opening or sealing of the valve at level c may be effected by hand in accordance with indications of thermometers which may be installed at x in the top of the roaster jacket, or x' in the roaster jacket, or x² through the roaster jacket into the material which is being treated in the roaster. In most practical cases, such thermometers will be thermostatic controllers which will automatically govern pressure in control chamber 36, to open 75

and close the outlet at *c* according as the roaster temperature varies up or down from the normal desired temperature.

In the present case, it is assumed that the boiler is designed for satisfactory operation at 6 lb. absolute, and should not operate at a pressure less than 2 lbs. absolute, which corresponds to a 4 inch mercury head. This is provided for by making the overflow level at least 4 inches above that of the vapor outlet of the valve *C*, at *c*. It will be understood, however, that this differential level may be 6 inches for a minimum 3 lb. opening pressure; or may be otherwise varied to suit conditions; also that this static differential may be interfered with and controlled by imposing a constant minimum and/or maximum for the operating variations of the control pressure as applied to the surface of the mercury in overflow chamber 36. Also a definite control pressure constantly or variably applied can be made to take care of widely different values of pressure that may be desired for boiler operations as against widely different pressures that may be required for roaster operations in special cases. In general, however, a normal predetermined static head and a desired set of static differentials should be embodied in the valve to suit special conditions and special kinds of work to be performed in the apparatus.

As before explained, the supply line 1, may have any desired number of roasters or the like operating in parallel with roaster *B*, and the control valves for the other roasters may be designed or operated for roaster jacket pressures and temperatures entirely different from those illustratively described in connection with roaster *B*.

While the primary function of the after condenser *D* is to act as a safety device to prevent the mercury vapor in the jacket of the roaster from getting too hot, and to equalize pressures on ends of the roaster, these primary functions are supplemented by a valuable secondary function, which is the gradual elimination of air from the system. No matter how small may be the amount of air left in the system when the boiler is vacuumized before heating, it will be sufficient to cause difficulty when the boiler is heated. In the system, as shown, such air will collect in said after condenser *D*, from which it may be removed from time to time by very slightly cracking valve 5. There is no danger of the mercury vapor itself passing into the vacuum pump, because any mercury vapor that is drawn into said condenser, is condensed therein and is returned to the boiler. Under certain conditions it may be found advantageous to run with valve 5 always cracked slightly, but in general this will be found unnecessary after the system has been in operation for a fairly long period with intermittent cracking of the valve as above described.

Where more than one roaster is operated on the same supply, 1, it is possible to arrange for proper division of loads to suit the requirements of each, by suitable adjustments of the respective valves 5, of the several roasters.

If it becomes necessary to shut down the equipment rapidly, because of chemical conditions in the material being treated, or for any other reason, the shut down may be accomplished most readily by opening up an air inlet into the line. This will cause boiling of the mercury in the boiler to cease immediately. But this method should be used only for emergency, as the air admitted to the vapor system tends to create trouble.

The sumps are useful to permit cleaning out mill scale and sludge. They should be cleaned out frequently when the equipment is first put into operation, but it will be found that the amount of mill scale obtainable from the sumps will diminish greatly, and when this has reached its minimum further cleaning out of these sumps will be unnecessary.

After operation, as described above, the system may be shut down, leaving mercury in the safety bubbler and in the valve. The levels in the valve *C* will then be found to remain in a position near or slightly below the line *d*, Fig. 6. It is preferable that the vacuum remain on the system during intermissions of operation, so that re-evacuation will be unnecessary. Even so, at restarting, it will be found good practice to put the vacuum pump on the system by opening valves 3, 4, 5 and 8, keeping 7 open and 6 closed, but not the control valve, until it is certain that the system is completely evacuated. The mercury boiler is then fired and operated with the valve *C* closed, as in Fig. 5, while the line pressure is gradually brought up to a minimum of 3 lbs. per square inch, whereupon normal operation of said valve 20 may be resumed, as above described.

It may be noted that the boiler shown in Fig. 1 has a diagrammatically indicated mercury level indicator, comprising an inverted U-tube the upper part of which is vacuumized to insure zero pressures on columns of mercury in the adjacent legs of the U. The levels of the respective columns are determined for one by the depth pressure of the liquid mercury in the boiler and for the other by the depth pressure of a compartment in which mercury is maintained at a higher level, in this case 3 inches higher, by condensation through a pipe connected with the vapor cavity of the boiler, above the liquid level. The height of the mercury in this trap being constant, variations in the level of the other will indicate actual liquid level in the boiler. As before stated, however, the boiler and the level indicator are not essential features of my present invention.

I claim:

1. A mercury vapor heating system including mercury boiling means, mercury condensing means and intermediate mercury liquid-sealed, pressure-operated valve means, embodying columns of liquid mercury having their surfaces exposed to inlet and outlet pressures respectively, in counterbalancing U-relation and each of vertical height sufficient to afford a desired differential depth pressure against the boiler pressure; and conduit means for returning condensate from the condensing element to the valve to replenish sealing liquid that is evaporated, entrained or forced out during normal operation.

2. A mercury vapor heating system including mercury boiling means, mercury condensing means and intermediate mercury liquid-sealed, pressure-operated valve means, embodying columns of liquid mercury having their surfaces exposed to inlet and outlet pressures respectively, in counterbalancing U-relation and each of vertical height sufficient to afford a desired differential depth pressure against the boiler pressure; a liquid overflow outlet determining a normal datum level for the liquid columns; and conduit means for returning condensate from the condensing element to the valve to replenish the sealing liquid evaporated, entrained or forced out during normal operation.

3. A mercury vapor heating system including

mercury boiling means, mercury condensing means and intermediate mercury liquid-sealed, pressure-operated valve means; embodying columns of liquid mercury having their surfaces exposed to inlet and outlet pressures respectively, in counterbalancing U-relation and each of vertical height sufficient to afford a desired differential depth pressure against the boiler pressure; a liquid overflow outlet determining a normal datum level for said columns; and conduit means for supplying liquid to restore the normal level after losses, as by evaporation, entrainment or overflow.

4. A mercury vapor heating system including mercury boiling means, mercury condensing means and intermediate mercury liquid-sealed, pressure-operated valve means, embodying columns of liquid mercury having their surfaces exposed to inlet and outlet pressures respectively, in counterbalancing U-relation, and each of vertical height sufficient to afford a desired differential depth pressure against the boiler pressure; a liquid overflow outlet a predetermined distance above the vapor inlet, predetermining a desired pressure differential at which the inlet will become unsealed; and conduit means for supplying liquid to restore the normal level after losses, as by evaporation, entrainment or overflow.

5. A mercury vapor heating system including mercury boiling means, mercury condensing means and intermediate mercury liquid-sealed, pressure-operated valve means, embodying columns of liquid mercury having their surfaces exposed to inlet and outlet pressures respectively, in counterbalancing U-relation, and each of vertical height sufficient to afford a desired differential depth pressure against the boiler pressure; a liquid overflow outlet a predetermined distance above the vapor inlet, predetermining a desired pressure differential at which the inlet will become unsealed; and conduit means for supplying liquid to restore the normal level after losses, as by evaporation, entrainment or overflow; said overflow being in a separate chamber communicating with said valve means through a U-trap affording a permanent-differential depth-pressure of liquid as against maximum gaseous pressure differentials either toward or away from the valve.

6. A mercury vapor heating system including mercury boiling means, mercury condensing means and intermediate mercury liquid-sealed, pressure-operated valve means, embodying columns of liquid mercury having their surfaces exposed to inlet and outlet pressures respectively, in counterbalancing U-relation, and each of vertical height sufficient to afford a desired differential depth pressure against the boiler pressure; a liquid overflow outlet a predetermined distance above the vapor inlet, predetermining a desired pressure differential at which the inlet will become unsealed; and conduit means for supplying liquid to restore the normal level after losses, as by evaporation, entrainment or overflow; said overflow being in a separate chamber communicating with said valve means through a U-trap affording a permanent-differential depth-pressure of liquid as against maximum gaseous pressure differentials either toward or away from the valve; and discharging its overflow through a similar U-trap affording depth pressure seal against maximum gaseous pressure differentials; together with means for applying variable fluid pressures to the surface of the overflow column between said traps, to open or close said valve

independently of the differential static pressures of the liquid columns.

7. A primarily evacuated heating system serially including a mercury boiler, a supply conduit for the mercury vapor, mercury vapor condensing means, a mercury condensate return conduit, a trap for said mercury condensate return conduit embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter thereby enclosing and defining inner and outer columns of condensate in counterbalancing U-relation. 5

8. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter thereby enclosing and defining inner and outer columns of condensate in counterbalancing U-relation, 15 said valve having a liquid overflow outlet a predetermined distance above the level of the vapor inlet and a condenser connection for supplying condensed mercury to replace that lost in operation of the device. 30

9. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter thereby enclosing and defining inner and outer columns of condensate in counterbalancing U-relation, 35 said valve having a liquid overflow outlet a predetermined distance above the level of the vapor inlet and a condenser connection for supplying condensed mercury to replace that lost in operation of the device. 45

10. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter thereby enclosing and defining inner and outer columns of condensate in counterbalancing U-relation, 50 said valve having a liquid overflow outlet a predetermined distance above the level of the vapor inlet and a condenser connection for supplying condensed mercury to replace that lost in operation of the device. 55

10. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter thereby enclosing and defining inner and outer columns of condensate in counterbalancing U-relation, said valve having a liquid overflow outlet a predetermined distance above the level of the vapor inlet and a condenser connection for supplying condensate in counterbalancing U-relation, 65

densed mercury to replace that lost in operation of the device.

11. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter thereby enclosing and defining inner and outer columns of condensate in counterbalancing U-relation designed to sustain a desired maximum differential depth pressure against the boiler pressure.

12. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a heat insulated downwardly extending vapor inlet conduit enclosed by a valve casing of substantially larger diameter thereby enclosing and defining inner and outer columns of condensate in counterbalancing U-relation designed to sustain a desired maximum differential depth pressure against the boiler pressure.

13. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a downwardly extending vapor inlet conduit enclosed by a valve casing of substantially larger diameter

thereby enclosing and defining inner and outer columns of condensate in counterbalancing U-relation, and having its top a substantial distance above its offtake to permit free upward projection of liquid mercury globules past the offtake.

14. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a heat insulated downwardly extending vapor inlet conduit enclosed by a valve casing of substantially larger diameter thereby enclosing and defining inner and outer columns of condensate in counterbalancing U-relation, said valve having a lateral vapor offtake to the condensing means above the maximum high level of the mercury in the outer leg, and having its top a substantial distance above said offtake to permit free upward projection of liquid mercury globules past the offtake.

15. A primarily evacuated heating system serially including a mercury boiler, a supply conduit for the mercury vapor, mercury vapor condensing means, a mercury condensate return conduit, a trap for said mercury condensate return conduit, embodying columns of liquid mercury in counterbalancing U-relation, and of sufficient vertical height to seal said mercury condensing means against maximum working boiler pressures; and a valve for maintaining a desired pressure drop between the lead conduit and the condensing means, said valve including a heat insulated downwardly extending vapor inlet conduit enclosed by a valve casing of substantially larger diameter thereby enclosing and defining inner and outer columns of condensate in counterbalancing U-relation, said valve having a lateral vapor offtake to the condensing means above the maximum high level of the mercury in the outer leg, and having its top a substantial distance above said offtake to permit free upward projection of liquid mercury globules past the offtake, and the top of said valve being inclined in a direction to deflect such mercury to the side of the valve opposite the offtake.

CROSBY FIELD.
